UNITED STATES PATENT OFFICE.

HUGH L. BRALY, OF CLARENDON, TEXAS.

OIL-BURNER.

1,015,288.

Specification of Letters Patent.

Patented Jan. 23, 1912.

Application filed November 27, 1909. Serial No. 530,151.

To all whom it may concern:

Be it known that I, HUGH L. BRALY, citizen of the United States, residing at Clarendon, in the county of Donley and State of Texas, have invented certain new and useful Improvements in Oil-Burners, of which the following is a specification.

My invention relates to devices for burning oil in stoves or furnaces and particularly to a construction adapted to be placed to a position within a stove above the grate surface thereof, providing a hearth or stove on which the oil is to be burned, and means for permitting a proper inlet of air to the fire generated on the hearth.

The invention consists in the arrangement of parts and details of construction set forth in the accompanying specification and more particularly stated in the claims appended.

For a full understanding of the invention reference is to be had to the following description and accompanying drawing, in which:—

Figure 1 is a sectional view of a stove showing my improved burner in section. Fig. 2 is an enlarged section through the air chamber of the burner. Fig. 3 is a perspective view of the burner detached from the stove. Fig. 4 is a like view to Fig. 1 showing a modified form of burner.

Corresponding and like parts are referred to in the following description and indicated in all the views of the accompanying drawing by the same reference characters.

Referring to these figures A designates a stove or firebox of any desired character, and B the grate thereof.

One form of my invention comprises a burner adapted to be inserted within the stove or firebox and to be placed on the top of the grate B therein. This burner is preferably made of one piece of refractory material such as fire brick, the pipes for conducting the oil to the burner being of course inserted therein after it is manufactured.

This form of my invention is shown in Figs. 1 to 4.

2 designates a body of refractory material, such as above described, having on one side thereof the burning trough or hearth 3. The bottom 4 of this hearth inclines toward the body 2 from the side edge of the hearth, and is also inclined from the middle toward the ends thereof so that the oil on the hearth may be evenly distributed.

Formed in the body 2 and extending

longitudinally therealong is the air chamber 5 which opens at the bottom of the body and extends over the grate B of the stove. This air chamber is connected to the hearth 3 by a plurality of slot-like openings 6, whereby air may be introduced along the whole face of the wall 7 of the body 2. To provide for the introduction of oil to the burner, I form the body 2 with the oil passage 8 which extends inward from the face of the wall 7 and which may extend either directly through the body portion 2 or extend to the middle of the body portion and then downward, as shown in Fig. 4. The interior of this passage is screw-threaded for engagement with an oil pipe 10 which extends out of the stove or firebox, and is connected to any suitable oil reservoir. This pipe is of course provided with suitable valves whereby the amount of oil flowing through the pipe may be regulated or checked entirely. In order to prevent the flames from the burning oil on the hearth 3 from igniting the oil as it passes out of the inlet passage 8 I provide on each side of the inlet passage, air passages 11 which communicate at their inner ends with the air chamber 5. Thus the flow of air out of said air passages 11 will force the flames away from the oil flowing out of the inlet 8 and thus prevent the ignition of said oil.

The operation of my invention is obvious. The burner is placed upon the grate B and thoroughly embedded in mortar D, care being taken not to allow the mortar to cover the lower end of the air chamber and thus prevent the passage of air up through the grate B and to the hearth. When the oil is lighted, the air passing to the hearth through the series of horizontal slots 6 introduces into the blaze sufficient air for the proper combustion of the oil, while the smoke from the burning oil passes out through the chimney of the stove or the firebox in the usual manner.

The form of my invention shown in Fig. 4 is practically the same as that previously described except that the oil feed pipe passes upward through the grate B instead of passing in through the side of the fire box or stove. In Fig. 4, 2^a designates the body of the burner of refractory material having a hearth 3^a and the air chamber 5^a. The air chamber is connected to the hearth by a plurality of slot-like openings as previously described. The oil passage 8^a is connected to

an oil pipe 10^a which extends up through the grate of the stove and through the air chamber 5^a, the outer end of the passage 8^a being closed by a plug 9^a. The operation of this form is precisely the same as that previously described.

My invention is simple, easily placed in position and thoroughly effective in practice. There are no complicated parts to clog and the body of refractory material which forms my burner retains and conducts sufficient heat to vaporize even crude oil so that it may be more readily burned.

Having thus described the invention what is claimed as new is:—

- 15 1. In an oil burner, a hollow body of refractory material open on its under side for its entire length and adapted to rest upon the grate of a stove, said body having a 20 hearth projecting out laterally therefrom at the base of the body, an oil supply duct extending through the interior of the hollow body and opening upon the face of the body above the hearth, and an air supply duct 25 spaced from the oil supply duct and communicating with the hollow interior of the body, said duct also opening upon the face of the hearth adjacent to the opening of the oil supply duct, said body being further 30 provided with a plurality of air openings

disposed on either side of the opening of the oil supply duct and extending along the wall of the hollow body above the bottom of the hearth.

2. In an oil burner, a hollow body of refractory material rectangular in section and open on its under side and adapted to rest upon the grate of a stove, said body having a hearth projecting out laterally therefrom at its base, the ends of said hearth having 35 upwardly extending walls joining the body, an oil supply duct extending through the interior of the hollow body and opening upon the face of the body above the hearth, air supply ducts disposed one on either side 40 of the oil duct and communicating with the hollow interior of the body and so arranged as to direct a blast of air outwardly to drive the flames away from the face of the body and away from the oil duct, and a plurality 45 of air openings disposed on each side of the oil duct, but below the same and extending along the face of the body and communicating with the hollow interior thereof.

In testimony whereof I affix my signature 50 in presence of two witnesses.
